UNITED STATES PATENT OFFICE.

EUCLID I. LA CHAPELLE, OF BEVERLY, MASSACHUSETTS.

MACHINE FOR WORKING AN UPPER ON A LAST.

1,168,011.

Specification of Letters Patent. Patented Jan. 11, 1916.

Application filed May 23, 1913. Serial No. 769,533.

To all whom it may concern:

Be it known that I, EUCLID I. LA CHAPELLE, of Beverly, in the county of Essex and State of Massachusetts, have invented certain new and useful Improvements in Machines for Working an Upper on a Last, of which the following is a specification.

This invention relates to machines for working an upper on a last, and more particularly to machines for this purpose of the general character shown in United States Patent No. 950,179, dated Feb. 22, 1910 and issued to the present applicant. It is not my purpose, of course, to claim anything already disclosed in the above patent.

The object of this invention is to provide a machine for working an upper on a last which will be rapid in operation and capable of producing more satisfactory work than that produced by those at present in use. The various features employed to the accomplishment of this object will be apparent to one skilled in the art to which the invention relates from the following description and accompanying drawings, in which:—

Figure 1 is a side elevation of my improved machine; Fig. 2 is a plan of the upper part of the machine shown in Fig. 1; Fig. 3 is a detail view of the end of the toe-engaging stop; Fig. 4 is a sectional detail view showing particularly the means for adjusting the toe-engaging stop; Fig. 5 is a sectional detail view of the device for pressing the last against its support; Fig. 6 is a detail view showing the means for adjusting the time operation of the mechanism for pulling the upper lengthwise of the last; Fig. 7 is a central longitudinal section of the upper part of the machine shown in Fig. 1; Fig. 8 is a section on the line 8—8, of Fig. 7; Fig. 9 is a sectional detail illustrating the manner in which the upper is pulled lengthwise of the last; Fig. 10 is a detail of the portion of the upper-pulling device which will be hereinafter described; and, Fig. 11 is a detail view of the stop for limiting the lengthwise movement of the last, which will be hereinafter described.

The machine illustrated in the drawings is of a lasting machine of the type commonly known as "bed lasters". In ma-

chines of this general type it is customary to employ wipers to wipe the upper over the bottom of the last. The wipers 1 shown particularly in Fig. 2 (these wipers are adapted to be positioned at the toe of the shoe whereby the upper may be simultaneously wiped over the bottom of the last at the sides of the toe and at the toe-end) are illustrated as being similar to the wipers shown in the patent to Stirckler, No. 477,788 dated June 28, 1892. In the present invention, a last presser is provided as is later described. The upper working devices are carried on a head 2 pivoted at 3 on a column 4 in order that the angle of the head may be adjusted to conform to the desires of various operators. Adjusting devices 5 are provided by which the head may be turned about its pivot.

A last-receiving spindle 6 is pivotally mounted at 7 on a slide 8. The slide is mounted in ways in the head 2 and normally urged toward the toe-end (the right in Fig. 2) of the head by a spring 9. Stops 10 and 11 are provided to limit the sliding movement of the spindle carrying slide. The spindle is made in the form of a bell crank having a projecting arm 12 which is normally elevated by a spring 13, thereby forcing the spindle about its pivotal point 7, toward the toe-end of the head. An adjustable stop 14 is provided to permit the limiting of its movement in this direction. The operator places the work into the machine preferably after the assembling of the upper to the heel-end of the last by suitable fastenings and prior to the insertion of additional fastenings to hold the upper in lasted condition, as the entire upper, including the heel portion may be lasted by the operator during the time the work is in the machine.

I want it well understood that the operator may last the upper, after the final actuation of the toe-support and during the time the work is in the machine, by any presently known hand method of lasting, not patented, that he may choose to adopt.

It is apparent from an inspection of Fig. 7 that adjustment of the stop 14 will vary the vertical position of the spindle 6 with respect to the other parts of the machine. In order to provide an independent adjustment of greater range, the spindle 6 is

screwed into its supporting member as indicated at 6', Fig. 7. A check nut 6'' is provided so that after the spindle has been raised or lowered by turning it in the support, it may be securely locked in position.

5 The operator puts a last having an upper placed thereon, on the spindle 6 and by turning the spindle about its pivot 7 and in some cases by sliding the spindle toward the rear against the action of the spring 9, the operator elevates the toe of the last until it can be placed on a toe-support 15 and against a stop 20. The action of the spring 9 forces the last forward until the end of 10 the last is engaged by the adjustable toe-engaging stop 20, (Fig. 4). The stop is provided with an index 21 as is shown in Fig. 3 to guide the operator in placing the big toe of the last in the same position at 15 each operation at any desirable angle on the toe support.

Up to this time the devices which engage the heel and the last have been held in their retracted position, shown in Fig. 7, by a treadle 22 connected by a rod 23 with a bell crank lever 24 which is connected with a slide 25 carrying the heel engaging device by a slot and pin connection 27, shown in Fig. 1.

30 The slide 25 carries shank engaging wings 26 which are spring pressed toward the work as shown in the aforementioned Patent No. 950,179. As is described in the present invention, when the slide 25 is moved toward the toe, the wipers or wings 26 act to hold the upper on the heel of the last and to hold it securely at the shank. In the present invention I provide an independently movable heel engaging device. This device comprises a yielding pad 27* of rubber or similar material mounted on a plate 28 which is in turn carried by two rods 29. The rods 29 pass through a block 30 carried by the slide 25 and are provided with collars 31 on their projecting ends. Springs 32 surround the rods 29 between the plates 28 and the block 30 so that the pad is normally spring-pressed toward the last. As the slide 25 is moved toward the last the pad 27* engages the heel of the last as shown in Fig. 1, after which the springs 32 yield so as to permit a continued movement of the slide and shank engaging wings without imparting any movement to the heel pad 27*.

55 The slide 25 is moved toward the last by two springs 35 one at each side of the machine which surround rods 36 upon which the head is mounted for longitudinal movement. Pressure on the treadle 22 compresses the springs 35 and when the springs are released the slide is thereby forced toward the last. The travel of the slide may be controlled by pressure upon the treadle 22. The treadle 22 may be depressed during 60 the time the toe-support back of the toe and

shank-engaging wings 26 are in engagement with the upper. The upper may then be pulled lengthwise of the last by friction upon the toe-support, or by the operator holding the upper against the toe-support, 70 and under the influence of the rearward movement of the shank-engaging wings and of the work thereby engaged, the upper may thus be pulled toward the toe. This rearward movement of the work whereby 75 the upper may be pulled lengthwise of the last may be advantageously employed to take off wrinkles from the upper, or to pull the upper lengthwise of the last and set the vamp-seam down on the last at the instep, 80 after, during, or preparatory to the pulling of the upper at the toe-end of the last. This pulling movement, back of the toe, as above described, will preferably take place prior to the application of fastenings at or near 85 the ball part of the last to hold the upper in lasted condition.

In the present invention, the toe-support performs the function of pulling the upper lengthwise of the last. The toe-support 90 also moves the last, as the movement of the toe-support is on the arc of a circle and as its movement toward the toe progresses, the upward movement of the toe-support accordingly progresses toward the last and 95 under the influence of that upward movement of the toe-support toward the last the last is moved. When the last is first placed in the machine, the upper is turned down in front of the toe-support as is shown in 100 Fig. 9. The toe-support is constructed to be moved toward the toe-end of the last as will be hereinafter described. When the movement toward the toe commences the operator holds the turned down portion of the upper against the toe-support with enough pressure to hold the upper from slipping so as to give a greater pull than that obtained by the friction of the toe-support on the upper. This is preferably 105 done, when the upper is heavy or the toe of the last high, as the strain upon the upper is then greater to properly work the upper, preparatory to the pulling over operation or preparatory to the toe wiping operation. 110

The toe-support is preferably of sufficient width to engage the marginal portion of the upper at each side and is preferably arched at the surface thereof to better adopt the shape of the last.

115 In operating a machine of the character described it has been found advantageous to first engage and overstrain the vamp of the upper by the toe-support and to release thereafter the toe-support, to some extent, 120 by pressure upon the treadle 22, by which the slide 25 may be moved and thereby the toe-support may be released and may be moved rearwardly under the influence of the reactionary strain of the vamp there- 125 130

against. After releasing some of the strain upon the vamp, as above explained, the sides of the vamp may then be pulled over the bottom of the last and fastenings may be applied to hold the vamp in lasted condition at the sides of the last, during the time the vamp is under engagement of the toe-support. In its broadest aspect, this overstraining movement upon the vamp by the toe-support is to positively strain and smooth out the vamp lengthwise of the last, which lengthwise straining movement is conducive to best results. In some cases, however, it may be advantageous to pull the vamp over the bottom of the last at the shank, or at, or near the ball of the last and to apply fastenings at those points to hold the vamp in lasted condition and thereafter, to pull the vamp over the bottom of the last at, or near the tip-seam of the vamp and to apply fastenings to hold that portion of the vamp in lasted condition. The vamp then is to be preferably pulled at the ball of the last and is to be fastened in lasted condition prior to releasing the toe-support and thereby of a part of the strain upon the vamp and thereafter, the vamp is to be pulled preferably at the tip-seam and is to be fastened in lasted condition after releasing the toe-support and thereby of a part of the strain upon the vamp. I want it well understood that the sides of the vamp may be pulled and fastened at other points instead of at the points above specified, without departing from the spirit of this invention. For example, with ill fitting vamps the shank part may be better lasted if pulled toward the last and fastened thereto in lasted condition during the time the vamp is in the overstrained condition, as above explained. For another example, when the heel portion is lasted at this machine fastenings may then be advantageously applied at the sides of the heel of the last, during the time the vamp is under the overstraining movement of the toe-support, as above explained.

In order to provide a suitable bearing for the upper on the toe-support, an elastic pad 36' is mounted on the upper end of a Y-shaped member 37. The pad is secured to the member by screws and also by corrugations 37' formed on the end of the member as shown particularly in Fig. 10. The member 37 is adjustably secured to a bell crank 38 which is pivoted at 39 on the head 2. A spring 40 surrounding the pivot stud 39 tends to hold the toe-support toward the rear of the last as is shown in Fig. 7. The other arm of the bell crank 38 engages a stud 41 mounted on the head 2 and provided with nuts 42 which are adapted to limit the movement of the bell crank in either direction.

The toe-support is moved about its pivot 39 toward the toe of the shoe by engaging

a part of the moving slide 25. A rod 43 is provided to contact with the bell crank. This rod may be adjusted with relation to the slide 25 so as to vary the time of movement of the bell crank by loosening nuts 46' 70 (see Fig. 6) on a threaded stud 47. The stud 47 is mounted in a block 44 which carries the rod 43. The block 44 is mounted for a lengthwise adjustment in a way 45. A scale 45' is provided to determine the 75 adjustment of the rod.

The movement of the toe-support may be retarded or the toe-support may be moved intermittently during the time of the pulling movement upon the upper by treadle 22 80 by which the action of the slide 25 may be controlled by the operator.

Mechanism is provided to determine the amount of movement imparted to the toe-support 15. As the toe-support pulls the 85 upper, this limits the pulling movement. This mechanism comprises a rod 50 mounted in an ear 51 depending from the slide 25. A set-screw 52 holds the rod in position. The rod passes through the opening in the 90 head 2 and is provided with collars 53 and 54. The collar 54 is adapted to limit the movement of the slide 25 away from the last, and the collar 53 is adapted to limit the movement of the slide toward the last. 95 After the slide 25 has moved toward the last until the collar 53 prevents further movement, which will also limit the pull on the upper, toward the toe, the operator uses the last presser (shown in Fig. 5) to press 100 the last downwardly against the toe-support. This last presser is especially intended for McKay shoes, as generally, wipers are not used on McKay shoes. This last presser is then used for compressing 105 the work against the toe-support after the pulling movement upon the upper, and thereby overcome the slipping back of the upper upon the toe-support during the application of fastenings at the sides to hold 110 the upper in lasted condition. In some cases, however, according to the, nature of the work operated upon, the spring 13 may hold the work against the toe-support with sufficient force so the last presser will be unnecessary during the application of fastenings. This last presser is not absolutely necessary with welt shoes or any other kind of shoes requiring a wiping operation at the toe, as then the wipers may be moved in 115 operative position and may contact with the work and hold the work against the toe-support during the time the fastenings are being applied at the sides. The wipers may be moved in operative position prior to the pulling movement upon the upper and may stop the work being moved by the toe-support and, of course, the pulling movement upon the upper.

The last presser comprises a work engag-

ing foot 55 which is normally elevated by a spring 56 mounted in a sleeve 57. The upper end of the work engaging foot is enlarged at 58 to form an abutment for one end of the spring 56 and further to form a bearing for the cam 59 which is mounted on a stud 60 and constructed to move the foot. A handle 61 is provided for the operator's use and a stop screw 62 is provided to permit limiting of the movement of the handle which also limits the downward movement of the work engaging foot. The last presser is adjustably mounted on a lug 63 carried by a fixed part of the head. After a last has been moved downwardly, as has been described, the upper has thereby been pulled farther toward the toe, as pressure upon the last forces the upper against the toe-support, down the incline of the last 20 at the instep thereof and toward the toe of the last under the influence of the movement of the work against the toe-support by the actuation of the last-presser. In some cases, as, for example, with very thin uppers, this 25 pulling movement upon the upper, under the influence of the movement of the last, as above explained, may be sufficient to properly set the upper lengthwise of the last. After the actuation of the last-presser the operator may use hand pincers to pull the upper over the sides of the last and over the toe-end and to apply suitable fastenings thereto. After having lasted the sides 30 of the upper, the handle 61 is turned to release the pressure on the last. The operator next presses the treadle 22 to some extent, which moves the slide 25 toward the rear. The last is carried with the slide 25 through the engagement of the wings 26. After the 35 last is moved to the rear enough to give the operator room to work, he pulls the upper over the toe-end of the last. Pressure on the treadle 22 is then released which causes the slide 25 to again move the work against the toe-engaging stop 20, and the operator may then wipe the entire toe portion and apply fastenings about the toe to hold the upper in wiped condition.

Provision is made for allowing the toe-support to be moved farther toward the toe after its movement to a predetermined distance from the toe. This is accomplished by providing a sliding block 65 mounted on the head 2 to engage the collar 53. A spring 66 is provided to hold the block normally elevated and in the path of the collar. At this time the operator may move the block away from the collar 53 so that the slide has a greater amount of movement. This excess 50 movement will cause the toe-support 15 to be moved a correspondingly greater distance toward the toe of the last.

It is to be noted, that at any time after the pulling operation upon the upper by the 55 toe support, with or without the excess

movement above referred to, fastenings may be applied at this machine near the tip-seam of the upper, at the top or at the sides of the last, near the bottom of the last to hold the upper in pulled condition on the last.

In order that the toe of the last may come in proper relation to the toe wipers, the last presser is again operated to move the shoe down. As the movement of the last presser is adjusted, it will be apparent that the shoe 75 may be forced downwardly into the proper position for the operation of the toe wipers. The toe wipers may then be operated in the usual manner. When the toe has been wiped and fastened, the last presser is released and 80 the treadle 22 is pressed to open the machine so that the work can be released.

The word, work, as used in the specification and claims, comprises within its meaning, when the context so permits, the last, 85 the upper, the insole and all parts relating thereto. The toe-end stop 20 is not absolutely necessary to this invention, as the spindle 6 may properly hold the last from endwise movement, with lasts that have the 90 spindle-engaging tubing set at uniform distance from the heel-end thereof.

The machine herein described is intended for handling an entire vamp, having a complete toe portion. In some cases, a complete toe portion includes a tip stitched on to the forepart of the vamp, which has been previously cut off, next to the location of the tip seam and which is termed by shoemakers as a cut-off vamp. This machine is primarily 100 intended for assembling the upper to the last, at the forepart thereof, preparatory to the pulling of the upper over the bottom of the last at the toe, which pulling-over operation may be performed by the operator.

It will be apparent that wipers may be provided if desired to operate on the upper at the heel, but I prefer to last the heel at a subsequent operation.

The combination of the upper pulling 110 means, of the actuating means therefor, of the spindle for supporting the last with heel engaging means for holding the upper toward the last, as herein described, constitutes a novel and very important feature of 115 this invention.

The combination of the spindle to support the last, of the upper pulling means, of the actuating means therefor with last moving means, at the forepart of the last, for moving the last toward the upper pulling means, as herein described, constitutes another novel and very important feature of this invention.

The combination of the upper engaging 125 means, at the top of the forepart of the last, back of the toe, and of the spindle for supporting the last and of last moving means, for moving the last lengthwise of the machine with last holding means, for 130

holding the last toward the upper engaging means and toward the spindle, during the movement of the last by the last moving means, as herein described, forms another novel and very important feature of this invention.

The combination of the spindle to support the last, of toe wipers, of last holding means, at the forepart of the last, to hold the last relatively to the toe wipers, of the upper pulling means with the actuating means therefor, to actuate the upper pulling means lengthwise of the last, toward the heel, during the time that the upper is being wiped over the bottom of the last by the toe wipers and during the time that the last is being held by the last holding means, as herein described, is also a novel and very important feature of this invention.

The combination of the spindle, of the upper pulling means, of the actuating means therefor with a treadle to predetermine the time that the upper pulling means may be actuated by the actuating means, as herein described, forms a novel and very important feature of this invention.

When the upper is very stretchy, back of the tip seam, or when the upper has not been firmly set on the last at precedent lasting operation, the toe wipers have then the tendency of pulling forward the center of the tip seam. This trouble being very common with toe wiping machines of the present day and such defective tips are generally termed "bow tips."

Pulling the upper toward the heel, during the toe wiping operation, as recited in some of the combinations of elements, overcomes this troublesome and serious defect of machines of the type herein described.

In operating a machine having combinations of elements, as recited in this patent, it has been found that the toe end stop was not absolutely necessary and it has also been found that in the general run of a shoe factory a frictional pulling operation upon the upper was sufficient and well adapted to a machine having toe wipers.

Turning the upper over the pulling means, as already described, or pulling the toe end of the upper, during the time of the frictional pulling operation upon the upper by the pulling means, is better adapted to machines for assembling the heel part of uppers to lasts, such machines being generally called "Assembling machines."

Turning the upper over the pulling means, as already described, or pulling the toe end of the upper over the toe end of the last, during the time of the frictional pulling operation upon the upper by the upper pulling means may be advantageous, even when a machine having toe wipers, as herein described, is used.

A novel and very important feature of

this invention resides in the provision of adjustable means for stopping the movement of the spindle lengthwise of the machine, relatively to the upper pulling means, for properly supporting lasts of various sizes, preparatory to the pulling operation and preparatory to the toe wiping operation. Another novel and important feature resides in the provision of adjustable means for stopping the movement of the upper pulling means lengthwise of the last, relatively to the spindle, for properly supporting lasts of various sizes, preparatory to the pulling operation and preparatory to the toe wiping operation. Both features may be used in combination, but, in operating a machine of the character described herein, it has been found sufficient to employ only one of the features disclosed in the drawings, namely, the stopping means for the spindle.

The two above noted features are especially valuable in combination with upper pulling means, as herein described, that engages the upper at one side only and therefore can support the last during the toe wiping operation. Moreover, the pulling means, engaging the upper at one side only, or the lining, as in the case of turned shoes, brings about better results at the pulling operation, as the upper and its lining are then smoothed out by the frictional pulling movement of the pulling means, which also holds both exactly to the lines of the last. When grippers are used, the upper and its lining being then both engaged and pulled thereby and the fabric lining being less elastic than the leather, the pulling movement of the grippers is thereby limited, with the result that the leather is often left in imperfect state after the completion of the pulling operation. These and other novel and important features, bringing about better results than were heretofore possible with machines of this general character, are specifically pointed out in the appended claims. It is also obvious that a machine of this character could be employed for the assembling operation, which is a step of lasting preparatory to passing the work to a pulling-over machine. Fastenings to hold the upper in lasted condition are not then absolutely necessary, as the operator may hold the upper in position on the last and pass the work to a pulling-over machine. At all steps of lasting, however, the upper is preferably pulled lengthwise of the last, as contemplated by this invention, prior to the application of fastenings at the bottom of the last at or near the ball part of the last to hold the upper in lasted condition, to permit free movement of the upper and of its seams down the incline of the last at the instep and toward the toe of the last.

This feature of the invention is fully as important as the feature of the lengthwise

movement of the upper and of its seams at the sides of the last.

Having described the best form of the invention at present known to me, what I claim as new and desire to secure by Letters Patent is:—

1. A machine for working an upper on a last, having, upper pulling means adapted to be positioned approximately at the center 10 of the top of the forepart of the last, back of the toe, arranged to permit the operator to turn the upper thereover and arranged to permit the operator to hold the upper in turned over position thereupon, during the pulling operation of said upper pulling means upon the upper.
2. A machine for working an upper on a last, having, upper pulling means adapted to be positioned approximately at the center 20 of the top of the forepart of the last, back of the toe, so arranged that the upper may be thereby pulled by friction and arranged to permit the operator to turn the upper thereover and arranged to permit the operator to hold the upper in turned over position thereupon, during the pulling operation of said upper pulling means upon the upper.
3. A machine for working an upper on a last, having, in combination, wipers adapted 30 to be positioned at one end of the last, so arranged that the upper may be thereby wiped over the bottom of the last, and upper pulling means adapted to be positioned approximately at the center of the top of the forepart of the last, back of the toe, so arranged that the upper may be thereby pulled lengthwise of the last, preparatory to the wiping operation of said wipers upon the upper, said upper pulling means being arranged to permit the operator to turn the upper thereover and arranged to permit the operator to hold the upper in turned over position thereupon, during the pulling operation of said upper pulling means upon the upper.
4. A machine for working an upper on a last, having, upper pulling means adapted to be positioned approximately at the center 50 of the top of the forepart of the last, back of the toe, so arranged that the last may be thereby supported in inverted position and arranged to permit the operator to turn the upper thereover and arranged to permit the operator to move said upper pulling means, during the time that the upper is in turned over position thereupon to cause said upper pulling means to pull the upper lengthwise of the last.
5. A machine for working an upper on a last, having, in combination, last supporting means adapted to be positioned at the rear part of the last, so arranged that the last may be thereby engaged independently 60 of the upper on the last, upper pulling

means adapted to be positioned approximately at the center of the top of the forepart of the last, back of the toe, so arranged that the upper may be turned thereover and last moving means adapted to be positioned relatively to the last, so arranged that the last may be thereby moved toward said upper pulling means, during the time that the upper is in turned over position upon said upper pulling means.

6. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be turned thereover, last moving means adapted to be positioned relatively to the last, so arranged that the last may be thereby moved toward said upper pulling means, during the time that the upper is in turned over position thereupon and last holding means adapted to be positioned relatively to the last and so arranged that the last may be thereby held toward said upper pulling means and toward said last supporting means, during the time of the pulling operation upon the upper by said upper pulling means.

7. A machine for working an upper on a last, having, in combination, upper pulling means adapted to be positioned approximately at the center of the top of the forepart of the last, back of the toe, arranged to permit the turning of the upper thereover and last moving means adapted to be positioned relatively to the last and so arranged that the last may be thereby moved, during the time that the upper is in turned over position upon said upper pulling means, for the purposes described.

8. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, arranged to permit the operator to turn the upper thereover, actuating means to actuate said upper pulling means, during the time that the upper is in turned over position upon said upper pulling means and heel engaging means adapted to be positioned relatively to the last and so arranged that the upper may be thereby held toward the last.

9. A machine for working an upper on a last, having, in combination, upper pulling means adapted to be positioned approximately at the center of the top of the fore-

- part of the last, back of the toe, arranged to permit the operator to turn the upper thereover and upper working means adapted to be positioned relatively to the upper and 5 arranged for coöperation upon the upper with said upper pulling means to effect a lengthwise pulling movement upon the upper, during the time that the upper is in turned over position upon said upper pulling 10 means.
10. A machine for working an upper on a last, having, in combination, last supporting means adapted to be positioned at the rear part of the last, so arranged that the last 15 may be thereby engaged independently of the upper on the last, upper pulling means adapted to be positioned approximately at the center of the top of the forepart of the last, back of the tip-seam of the upper on 20 the last, arranged to permit the upper to be turned thereover, actuating means to actuate said upper pulling means, during the time that the upper is in turned over position thereupon and last holding means adapted 25 to be positioned relatively to the shoe and so arranged that the last and the upper may be thereby held against said upper pulling means, and arranged to permit the upper to move toward the heel of the last and against 30 said upper pulling means, under the influence of the reactionary strain of the upper after the turned over part of the upper has been returned to its normal position on the last.
- 35 11. A machine for working an upper on a last, having, in combination, last supporting means adapted to be positioned at the rear part of the last, so arranged that the last may be thereby engaged independently of 40 the upper on the last, upper pulling means adapted to be positioned approximately at the center of the top of the forepart of the last, back of the toe, so arranged that the upper may be thereby engaged at one side 45 only, springs to actuate said upper pulling means lengthwise of the last, toward the toe and heel engaging means, so arranged that the upper may be thereby held toward the last.
- 50 12. A machine for working an upper on a last, having, in combination, last supporting means adapted to be positioned at the rear part of the last, so arranged that the last may be thereby engaged independently of 55 the upper on the last, upper pulling means adapted to be positioned approximately at the center of the top of the forepart of the last, back of the toe, so arranged that the upper may be thereby engaged at one side 60 only, springs to actuate said upper pulling means lengthwise of the last, toward the toe, a lever positioned relatively to said springs, connections positioned relatively to said lever and to said springs, so arranged 65 that the time of the actuation of said springs
- may be thereby controlled and heel engaging means, so arranged that the upper may be thereby held toward the last.
13. A machine for working an upper on a last, having, in combination, last supporting 70 means adapted to be positioned at the rear part of the last, so arranged that the last may be thereby engaged independently of the upper on the last, upper pulling means adapted to be positioned approximately at 75 the center of the top of the forepart of the last, back of the toe, heel engaging means, so arranged that the upper may be thereby held toward the last, and a carriage for supporting said heel engaging means, arranged 80 to contact with and actuate said upper pulling means.
14. A machine for working an upper on a last, having, in combination, last supporting means adapted to be positioned at 85 the rear part of the last, so arranged that the last may be thereby engaged independently of the upper on the last, upper pulling means adapted to be positioned approximately at the center of the top of the 90 forepart of the last, back of the toe, heel engaging means, so arranged that the upper may be thereby held toward the last, a carriage for supporting said heel engaging means, arranged to contact with and actuate said upper pulling means and heel engaging means adapted to be positioned relatively to the last and so arranged that the upper may be thereby held toward the last.
- 95 15. A machine for working an upper on a last, having, in combination, last supporting means adapted to be positioned at the rear part of the last, so arranged that the last may be thereby engaged independently of the upper on the last, movable upper pulling means adapted to be positioned approximately at the center of the top of the forepart of the last, back of the toe, stopping means positioned relatively to said upper pulling means, so arranged that said upper pulling means may be thereby stopped from return movement after its pulling movement upon the upper and heel engaging means adapted to be positioned relatively to the last and so arranged that the upper may be thereby held toward the last.
- 100 16. A machine for working an upper on a last, having, in combination, last supporting means adapted to be positioned at the rear part of the last, so arranged that the last may be thereby engaged independently of the upper on the last, upper pulling means adapted to be positioned at the 105 forepart of the last, so arranged that the upper may be thereby pulled lengthwise of the last, heel engaging means, so arranged that the upper may be thereby held toward the last, actuating means for said heel en-
- 110 115 120 125 130

gaging means, additional actuating means for said heel engaging means and a carriage for supporting said heel engaging means, so arranged that movement thereof 5 may cause movement of said upper pulling means.

17. A machine for working an upper on a last, having, in combination, movable upper pulling means adapted to be positioned at the forepart of the last, so arranged that the upper may be thereby pulled lengthwise of the last, toward the toe, heel engaging means, so arranged that the upper may be thereby held toward the last and a carriage for supporting said heel engaging means, arranged for holding said upper pulling means from movement toward the heel after its lengthwise pulling movement, toward the toe.

18. A machine for working an upper on a last, having, in combination, movable upper pulling means adapted to be positioned at the forepart of the last, arranged for movement lengthwise of the last, last 25 supporting means adapted to be positioned at the rear part of the last, so arranged that the last may be thereby engaged independently of the upper on the last, springs positioned relatively to said movable upper pulling means and to said last supporting means to yieldingly hold said upper pulling means toward the toe and additional holding means positioned relatively to said upper pulling means, so arranged that said upper pulling means may be thereby held non-yieldingly from movement.

19. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means for said upper pulling means and last holding means adapted to be positioned relatively to the last and so arranged that the last may be thereby held toward said upper pulling means and toward said last supporting means.

20. A machine for working an upper on a last, having, in combination, last supporting means adapted to be positioned at the rear part of the last, so arranged that the last may be thereby engaged independently of the upper on the last, work supporting means adapted to be positioned approximately at the center of the top of the forepart of the last, back of the toe, so arranged that the upper may be thereby pulled lengthwise of the last, wipers adapted to be positioned at one end of the last, so arranged that the upper may be

thereby wiped over the bottom of the last, after the pulling operation upon the upper by said work supporting means, and last moving means adapted to be positioned relatively to the last, so arranged that the last may be thereby moved against said work supporting means, during the time that the upper is being wiped over the bottom of the last by said wipers, said work supporting means being arranged for movement lengthwise of the last, under the influence of the movement of the last by said last moving means.

21. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, springs to actuate said upper pulling means lengthwise of the last, toward the toe, heel engaging means, so arranged that the upper may be thereby held toward the last and springs to actuate said heel engaging means.

22. A machine for working an upper on a last, having, in combination, upper pulling means adapted to be positioned approximately at the center of the top of the forepart of the last, back of the toe, actuating means to actuate said upper pulling means lengthwise of the last and stopping means positioned relatively to said actuating means, so arranged that the actuation of said upper pulling means toward the toe by said actuating means may be thereby stopped and arranged to be rendered inoperative to permit further actuation of said upper pulling means by said actuating means.

23. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, arranged for movement lengthwise of the last, stopping means positioned relatively to said upper pulling means, so arranged that the movement of said upper pulling means toward the toe may be thereby stopped and heel engaging means adapted to be positioned relatively to the last and so arranged that the last may be thereby held toward said upper pulling means and toward said last supporting means.

24. A machine for working an upper on a last, having, in combination, last supporting means adapted to be positioned at the

rear part of the last, so arranged that the last may be thereby engaged independently of the upper on the last, wipers adapted to be positioned at one end of the last, so arranged that the upper may be thereby wiped over the bottom of the last, upper pulling means adapted to be positioned approximately at the center of the top of the forepart of the last, back of the toe, so arranged that the upper may be thereby engaged at one side only and heel engaging means, so arranged that the upper may be thereby held toward the last, substantially as described.

25. A machine for working an upper on a last, having, in combination, heel engaging means, so arranged that the upper may be thereby held toward the last, toe wipers, so arranged that the upper may be thereby wiped over the bottom of the last, upper pulling means adapted to be positioned approximately at the center of the top of the forepart of the last, back of the toe, arranged for movement lengthwise of the last, yielding actuating means for said upper pulling means, and adjustable stopping means positioned relatively to said upper pulling means, so arranged that said upper pulling means may be thereby stopped from movement lengthwise of the last, relatively to said heel engaging means, to properly support lasts of various sizes, preparatory to the pulling operation of said upper pulling means upon the upper and preparatory to the wiping operation of said toe wipers upon the upper.

26. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only and arranged for movement lengthwise of the last and adjustable stopping means positioned relatively to said upper pulling means, so arranged that said upper pulling means may be thereby stopped from movement lengthwise of the last, relatively to said last supporting means, to properly support lasts of various sizes, preparatory to the pulling operation of said upper pulling means upon the upper.

27. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means for said upper pulling means, heel

engaging means so arranged that the upper may be thereby held toward the last, a carriage for supporting said heel engaging means, arranged for movement toward and away from the last, stopping means positioned relatively to said carriage, so arranged that said carriage may be thereby stopped from movement toward the last, and arranged to be operative only during the movement of said carriage toward the last and heel engaging means adapted to be positioned relatively to the last and so arranged that the upper may be thereby held toward the last means.

28. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, last moving means adapted to be positioned relatively to the last, so arranged that the last may be thereby moved lengthwise of the machine to cause said upper pulling means to pull the upper lengthwise of the last, under the influence of the movement of the last by said last moving means, said last moving means being arranged to hold the last from lateral movement and heel engaging means adapted to be positioned relatively to the last and so arranged that the upper may be thereby held toward the last.

29. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, arranged for movement lengthwise of the last, adjustable stopping means positioned relatively to said upper pulling means, so arranged that the movement of said upper pulling means toward the toe may be thereby stopped at predetermined points and heel engaging means adapted to be positioned relatively to the last and so arranged that the upper may be thereby held toward the last.

30. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, arranged for movement lengthwise of the last, adjustable stopping means positioned relatively to said upper pulling means, so arranged that the movement of said upper pulling means toward the toe may be thereby stopped at predetermined points and heel engaging means adapted to be positioned relatively to the last and so arranged that the upper may be thereby held toward the last.

tively to said upper pulling means, so arranged that the movement of said upper pulling means toward the toe may be thereby stopped at predetermined points and additional adjustable stopping means positioned relatively to said upper pulling means, so arranged that the movement of said upper pulling means toward the heel may be thereby stopped at predetermined points.

31. A machine for working an upper on a last, having, in combination, last supporting means adapted to be positioned at the rear part of the last, so arranged that the last may be thereby engaged independently of the upper on the last, upper pulling means adapted to be positioned at the forepart of the last, yielding last holding means adapted to be positioned relatively to the last, so arranged that the last may be thereby held from lengthwise movement in one direction and non-yielding last holding means adapted to be positioned relatively to the last, so arranged that the last may be thereby held from lengthwise movement in the opposite direction.

32. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe and sole holding means adapted to be positioned relatively to the sole on the last and so arranged that the sole may be thereby held from movement on the last, during the pulling operation upon the upper by said upper pulling means.

33. A machine for working an upper on a last, having, in combination, upper pulling means adapted to be positioned approximately at the center of the top of the forepart of the last, back of the toe yielding actuating means for said upper pulling means, last supporting means adapted to be positioned at the rear part of the last so arranged that the last may be thereby engaged independently of the upper on the last and arranged for movement lengthwise of the machine and stopping means positioned relatively to said last supporting means, so arranged that said last supporting means may be thereby stopped from lengthwise movement at predetermined points, relatively to said upper pulling means.

34. A machine for working an upper on a last, having, in combination, last supporting means adapted to be positioned at the rear part of the last, so arranged that the last may be thereby engaged independently of the upper on the last, wipers adapted

to be positioned at one end of the last, so arranged that the upper may be thereby wiped over the bottom of the last, upper pulling means adapted to be positioned approximately at the center of the top of the forepart of the last, back of the toe and yielding heel engaging means adapted to be positioned relatively to the last and so arranged that the upper may be thereby held toward the last.

35. A machine for working an upper on a last, having, in combination, upper pulling means adapted to be positioned approximately at the center of the forepart of the last, back of the toe, so arranged that the upper may be thereby engaged at one side only, yielding actuating means for said upper pulling means, a last pin to support the last, supporting means, arranged for movement lengthwise of the machine, to support said last pin, actuating means for said supporting means and stopping means, so arranged that said supporting means may be thereby stopped and held from movement at predetermined points for lasts of various sizes.

36. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, arranged for movement lengthwise of the last, stopping means positioned relatively to said upper pulling means, so arranged that the movement of said upper pulling means toward the toe of the last may be thereby stopped and last holding means adapted to be positioned relatively to the last and so arranged that the last may be thereby held toward said last supporting means.

37. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe and upper holding means adapted to be positioned at the shank part of the last.

38. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe and last moving means

- adapted to be positioned relatively to the last, so arranged that the last may be thereby moved against said upper pulling means, said upper pulling means being arranged 5 for movement lengthwise of the last to permit said upper pulling means to pull the upper lengthwise of the last, under the influence of the movement of the last by said last moving means.
- 10 39. A machine for working an upper on a last, having, in combination, upper pulling means adapted to be positioned approximately at the center of the top of the forepart of the last, back of the toe, yielding 15 actuating means for said upper pulling means, a last pin to support the last, a slide to support said last pin, arranged for movement lengthwise of the machine and stopping means positioned relatively to said 20 slide and so arranged that said slide may be thereby stopped from movement at predetermined points.
40. A machine for working an upper on a last, having, in combination, last supporting 25 means adapted to be positioned at the rear part of the last, so arranged that the last may be thereby engaged independently of the upper on the last, upper pulling means adapted to be positioned approximately at 30 the center of the top of the forepart of the last, back of the toe, yielding actuating means for said upper pulling means, limiting means positioned relatively to said upper pulling means to limit the movement 35 of said upper pulling means and heel engaging means adapted to be positioned relatively to the last and so arranged that the upper may be thereby held toward the last.
41. A machine for working an upper on a 40 last, having, in combination, upper pulling means adapted to be positioned approximately at the center of the top of the forepart of the last, back of the toe, so arranged that the upper may be thereby engaged at 45 one side only and yielding actuating means for said upper pulling means movable last supporting means adapted to be positioned at the rear part of the last, so arranged that the last may be thereby engaged independently of the upper on the last and arranged 50 for movement lengthwise of the machine and holding means positioned relatively to said movable last supporting means, so arranged that said movable last supporting 55 means may be thereby held from movement at predetermined points lengthwise of the machine.
42. A machine for working an upper on a last, having, in combination, last supporting means adapted to be positioned at the rear part of the last, so arranged that the last may be thereby engaged independently of the upper on the last, movable, upper pulling means adapted to be positioned approxi- 65 mately at the center of the top of the forepart of the last, back of the toe, last moving means adapted to be positioned relatively to the last, so arranged that the last may be thereby moved lengthwise of the machine to cause said upper pulling means to pull the 70 upper lengthwise of the last, under the influence of the movement of the last by said last moving means, stopping means positioned relatively to said upper pulling means, so arranged that the movement of 75 said upper pulling means may be thereby stopped at predetermined points, prior to the movement of the last by said last moving means and heel engaging means adapted to be positioned relatively to the last 80 and so arranged that the upper may be thereby held toward the last.
43. A machine for working an upper on a last, having, in combination, last supporting means adapted to be positioned at the rear part of the last, so arranged that the last may be thereby engaged independently of the upper on the last, upper pulling 85 means adapted to be positioned approximately at the center of the top of the forepart of the last, back of the toe, last moving means adapted to be positioned relatively to the last, so arranged that the last may be thereby moved lengthwise of the machine to cause said upper pulling means to pull the 90 upper lengthwise of the last, under the influence of the movement of the last by said last moving means and heel engaging means adapted to be positioned relatively to the last and so arranged that the upper may be 95 thereby held toward the last and arranged for movement, under the influence of the movement of the last by said last moving means.
44. A machine for working an upper, or 100 a last, having, in combination, upper pulling means adapted to be positioned relatively to the upper, upper holding means adapted to be positioned at the rear part of the last, so arranged that the upper may be thereby held toward the lines of the last, supporting means for said upper holding means and adjusting means positioned relatively to said supporting means, so arranged that said supporting means may be thereby 110 adjusted in the line of the length of the last.
45. A machine for working an upper on a last, having, in combination, last supporting means adapted to be positioned at the rear 115 part of the last, so arranged that the last may be thereby engaged independently of the upper on the last, upper pulling means adapted to be positioned approximately at the center of the top of the forepart of the last, back of the toe, actuating means for 120 said upper pulling means, last holding means adapted to be positioned relatively to the last and additional last holding means 125

- adapted to be positioned relatively to the last, all said last holding means being so arranged that the last may be thereby held toward said upper pulling means and toward said last supporting means.
46. A machine for working an upper on a last, having, in combination, upper pulling means adapted to be positioned approximately at the center of the top of the forepart of the last, back of the toe, upper holding means adapted to be positioned at the rear part of the last, so arranged that the upper may be thereby held toward the lines of the last, supporting means for said upper holding means and adjusting means positioned relatively to said supporting means, so arranged that said supporting means may be thereby adjusted in the line of the length of the last.
47. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, arranged to permit the last to be moved rearwardly and thereagainst to cause said upper pulling means to pull the upper forwardly, under the influence of the rearward movement of the last, last holding means adapted to be positioned relatively to the last, so arranged that the last may be thereby held from forward movement, after the pulling operation upon the upper by said upper pulling means and additional heel engaging means adapted to be positioned relatively to the last and so arranged that the last may be thereby held toward said upper pulling means and toward said last supporting means.
48. A machine for working an upper on a last, having, in combination, last supporting means adapted to be positioned at the rear part of the last, so arranged that the last may be thereby engaged independently of the upper on the last, wipers adapted to be positioned at one end of the last, so arranged that the upper may be thereby wiped over the bottom of the last, upper pulling means adapted to be positioned approximately at the center of the top of the forepart of the last, back of the toe, so arranged that the upper may be thereby pulled lengthwise of the last, last holding means adapted to be positioned relatively to the last, so arranged that the last may be thereby held from movement against the strain of the pulling movement upon the upper by said upper pulling means and arranged to permit the toe-end of the upper to be pulled over the bottom of the last, during the time of the pulling movement upon the upper by said upper pulling means and additional

heel engaging means adapted to be positioned relatively to the last and so arranged that the upper may be thereby held toward the last.

49. A machine for working an upper on a last, having, in combination, upper pulling means adapted to be positioned approximately at the center of the top of the forepart of the last, back of the toe, yielding last moving means adapted to be positioned relatively to the last, so arranged that the last may be thereby moved in one direction lengthwise of the machine and non-yielding last moving means adapted to be positioned relatively to the last and so arranged that the last may be thereby moved in the opposite direction lengthwise of the machine.

50. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, non-yielding last moving means adapted to be positioned relatively to the last, so arranged that the last may be thereby moved lengthwise of the machine to cause said upper pulling means to pull the upper lengthwise of the last, under the influence of the movement of the last by said non-yielding last moving means and heel engaging means adapted to be positioned relatively to the last and so arranged that the upper may be thereby held toward the last.

51. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, last moving means adapted to be positioned relatively to the last, so arranged that the last may be thereby moved to cause said upper pulling means to pull the upper lengthwise of the last, under the influence of the movement of the last by said last moving means and additional last moving means adapted to be positioned relatively to the last and so arranged that the last may be thereby moved toward said upper pulling means and toward said last supporting means.

52. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the

last, back of the toe, so arranged that the upper may be thereby engaged at one side only, movable upper working means adapted to be positioned relatively to the last, so arranged that movement thereof may cause movement of said upper pulling means and heel engaging means adapted to be positioned relatively to the last and so arranged that the upper may be thereby held toward the last.

53. A machine for working an upper on a last, having, in combination, last supporting means adapted to be positioned at the rear part of the last, so arranged that the last may be thereby engaged independently of the upper on the last, movable upper pulling means adapted to be positioned approximately at the center of the top of the forepart of the last, back of the toe, arranged for movement lengthwise of the last and last moving means adapted to be positioned relatively to the last, so arranged that the last may be thereby moved toward said movable upper pulling means to cause said movable upper pulling means to move lengthwise of the last and to pull the upper lengthwise of the last, under the influence of the movement of the last by said last moving means, said movable upper pulling means being arranged for movement toward the toe or toward the heel of the last, under the influence of the movement of the last by said last moving means.

54. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, last engaging means adapted to be positioned relatively to the last, so arranged that the last may be thereby engaged and moved against said upper pulling means, said upper pulling means being arranged for movement lengthwise of the last to permit said upper pulling means to pull the upper lengthwise of the last under the influence of the movement of the last by said last moving means and wipers adapted to be positioned at one end of the last, so arranged that the upper may be thereby wiped over the bottom of the last, after the lengthwise pulling movement upon the upper by said upper pulling means and during the time that said last engaging means is in engagement with the last.

55. A machine for working an upper on a last, having, in combination, upper pulling means adapted to be positioned approximately at the center of the top of the forepart of the last, back of the toe, arranged to permit the turning of the upper thereover and means to cause said upper pulling

means to pull the upper, during the time that the upper is in turned over position upon said upper pulling means, as and for the purposes described.

56. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means for said upper pulling means, a lever positioned relatively to said actuating means, connections positioned relatively to said actuating means and to said lever, so arranged that the operator may thereby control the actuation of said actuating means and heel engaging means, so arranged that the upper may be thereby held toward the last.

57. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, yielding actuating means to actuate said upper pulling means lengthwise of the last and heel engaging means adapted to be positioned relatively to the last and so arranged that the upper may be thereby held toward the last.

58. A machine for working an upper on a last, having, in combination, movable upper pulling means adapted to be positioned approximately at the center of the top of the forepart of the last, back of the toe, arranged for movement lengthwise of the last, stopping means positioned relatively to said movable upper pulling means, so arranged that the movement of said movable upper pulling means may be thereby stopped toward the toe of the last, heel engaging means so arranged that the upper may be thereby held toward the last, moving means for said heel engaging means and stopping means positioned relatively to said heel engaging means and so arranged that the movement of said heel engaging means may be thereby stopped at predetermined points.

59. A machine for working an upper on a last, having, in combination, upper pulling means adapted to be positioned approximately at the center of the top of the forepart of the last, back of the toe, so arranged that the upper may be thereby engaged at one side only and yielding actuating means for said upper pulling means, last supporting means adapted to be positioned at the rear part of the last, so arranged that the

- last may be thereby engaged independently of the upper on the last and arranged for movement lengthwise of the last, stopping means positioned relatively to said last supporting means, so arranged that said last supporting means may be thereby stopped from movement at predetermined points and heel engaging means adapted to be positioned relatively to the last and so arranged 10 that the upper may be thereby held toward the last.

60. A machine for working an upper on a last, having, in combination, last supporting means adapted to be positioned at the 15 rear part of the last, so arranged that the last may be thereby engaged independently of the upper on the last, upper pulling means adapted to be positioned approximately at the center of the top of the forepart of the last, back of the toe, arranged for free movement lengthwise of the last, actuating means for said upper pulling means and heel engaging means adapted to be positioned relatively to the last and so 20 arranged that the upper may be thereby held toward the last.

61. A machine for working an upper on a last, having, in combination, toe wipers, so arranged that the upper may be thereby 30 wiped over the bottom of the last, upper pulling means adapted to be positioned approximately at the center of the top of the forepart of the last, back of the toe, actuating means for said upper pulling means and last moving means adapted to be positioned relatively to the last and so arranged that the last may be thereby moved against said upper pulling means, during the time that the upper is being worked on the last by 35 40 said toe wipers.

62. A machine for working an upper on a last, having, in combination, upper pulling means adapted to be positioned approximately at the center of the top of the forepart of the last, back of the toe, last supporting means adapted to be positioned at the rear part of the last, so arranged that the last may be thereby engaged independently of the upper on the last, a carriage for 45 supporting said last supporting means and yielding actuating means for said carriage.

63. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, a carriage for supporting said last supporting means and actuating means for said carriage.

64. A machine for working an upper on a last, having, in combination, last supporting means adapted to be positioned at the

70 rear part of the last, so arranged that the last may be thereby engaged independently of the upper on the last, upper pulling means adapted to be positioned approximately at the center of the top of the forepart of the last, back of the toe, actuating means for said upper pulling means, additional independent actuating means for said upper pulling means and heel engaging means adapted to be positioned relatively to the last and so arranged that the upper 75 may be thereby held toward the last.

65. A machine for working an upper on a last, having, in combination, last supporting means adapted to be positioned at the 80 rear part of the last, so arranged that the last may be thereby engaged independently of the upper on the last, upper pulling means adapted to be positioned approximately at the center of the top of the forepart of the last, back of the toe, arranged for movement lengthwise of the last, actuating means to actuate said upper pulling means lengthwise of the last, said upper pulling means being arranged for movement 85 by the operator, after the termination of the actuation of said upper pulling means by said actuating means, to cause said upper pulling means to release its straining movement upon the upper to some extent, preparatory to the application of fastenings to hold the upper on the last as pulled by said upper pulling means and heel engaging means adapted to be positioned relatively to the last and so arranged that the upper 90 may be thereby held toward the last.

66. A machine for working an upper on a last, having, in combination, last supporting means adapted to be positioned at the rear part of the last, so arranged that the last may be thereby engaged independently of the upper on the last, heel engaging means, upper pulling means so arranged that the upper may be thereby held toward the last, adapted to be positioned at the forepart of the last and a single actuating means for said upper pulling means and for said heel engaging means.

67. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means for said upper pulling means, toe wipers, so arranged that the upper may be thereby wiped over the bottom of the last, last moving means adapted to be positioned relatively to the last, arranged for movement toward the last and so arranged that the last may be thereby moved toward said upper pulling means and limiting means positioned rela- 125 130

tively to said last moving means to limit the movement of said last moving means toward the last.

68. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means for said upper pulling means, limiting means positioned relatively to said actuating means, so arranged that the limit of the actuation of said actuating means may be thereby predetermined and heel engaging means adapted to be positioned relatively to the last and so arranged that the upper 20 may be thereby held toward the last.

69. A machine for working an upper on a last, having, in combination, last supporting means adapted to be positioned at the rear part of the last, so arranged that the last 25 may be thereby engaged independently of the upper on the last, upper pulling means adapted to be positioned approximately at the center of the top of the forepart of the last, back of the toe, so arranged that the 30 upper may be thereby engaged at one side only, actuating means for said upper pulling means and heel engaging means, so arranged that the upper may be thereby held toward the last, substantially as described.

70. A machine for working an upper on a last, having, in combination, upper pulling means adapted to be positioned approximately at the center of the top of the forepart of the last, back of the toe, last moving means adapted to be positioned relatively to the last, so arranged that the last 40 may be thereby moved lengthwise of the machine to cause said upper pulling means to pull the upper lengthwise of the last, under the influence of the movement of the last by said last moving means, a lever positioned relatively to said last moving means, connections positioned relatively to said last moving means and to said lever, so arranged 45 that the movement of said last moving means may be thereby controlled and heel engaging means adapted to be positioned relatively to the last and so arranged that the upper may be thereby held toward the last.

71. A machine for working an upper on a last, having, in combination, last supporting means adapted to be positioned at the rear part of the last, so arranged that the last 50 may be thereby engaged independently of the upper on the last, upper pulling means adapted to be positioned approximately at the center of the top of the forepart of the last, back of the toe, a last pin to support the last and actuating means to actuate said last

pin lengthwise of the machine to move the last toward said upper pulling means and heel engaging means adapted to be positioned relatively to the last and so arranged that the upper may be thereby held toward the last. 70

72. A machine for working an upper on a last, having, in combination, last supporting means adapted to be positioned at the rear part of the last, so arranged that the last 75 may be thereby engaged independently of the upper on the last, upper pulling means adapted to be positioned approximately at the center of the top of the forepart of the last, back of the toe, yielding actuating means to actuate said upper pulling means lengthwise of the last, stopping means positioned relatively to said upper pulling means, so arranged that said upper pulling means may be thereby stopped from movement toward the heel, after the pulling operation upon the upper toward the toe by said upper pulling means and heel engaging means adapted to be positioned relatively to the last and so arranged that the upper may 80 be thereby held toward the last. 85

73. A machine for working an upper on a last, having, in combination, last supporting means adapted to be positioned at the rear part of the last, so arranged that the last 90 may be thereby engaged independently of the upper on the last, upper pulling means adapted to be positioned approximately at the center of the top of the forepart of the last, back of the toe, actuating means to 95 actuate said upper pulling means lengthwise of the last, toward the toe, said upper pulling means being arranged for movement toward the heel independently of said actuating means, to permit the operator to properly position said upper pulling means relatively to the upper on the last, preparatory to the actuation of said actuating means and heel engaging means adapted to be positioned relatively to the last and so arranged that the upper may be thereby held toward the last. 100 105 110

74. A machine for working an upper on a last, having, in combination, last supporting means adapted to be positioned at the rear part of the last, so arranged that the last 115 may be thereby engaged independently of the upper on the last, upper pulling means adapted to be positioned approximately at the center of the top of the forepart of the last, back of the toe, actuating means for said upper pulling means and limiting means positioned relatively to said actuating means to limit the extent of the actuation of said actuating means. 120 125

75. A machine for working an upper on a last, having, in combination, last supporting means adapted to be positioned at the rear part of the last, so arranged that the last may be thereby engaged independently 130

of the upper on the last, upper pulling means adapted to be positioned approximately at the center of the top of the forepart of the last, back of the toe, a lever for supporting said upper pulling means, actuating means to actuate said lever lengthwise of the last, an addition lever positioned relatively to said first mentioned lever, connections positioned relatively to said levers, so arranged that the actuation of said first mentioned lever may be thereby controlled and heel engaging means adapted to be positioned relatively to the last and so arranged that the upper may be thereby held toward the last.

76. A machine for working an upper on a last, having, in combination, last supporting means adapted to be positioned at the rear part of the last, so arranged that the last may be thereby engaged independently of the upper on the last, movable upper pulling means adapted to be positioned approximately at the center of the top of the forepart of the last, back of the toe, stopping means positioned relatively to said upper pulling means to stop the movement of said upper pulling means and additional stopping means positioned relatively to said upper pulling means to stop the movement of said upper pulling means.

77. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means to actuate said upper pulling means lengthwise of the last and controlling means positioned relatively to said actuating means, so arranged that the time of the actuation of said actuating means may be thereby controlled.

78. A machine for working an upper on a last, having, in combination, last supporting means adapted to be positioned at the rear part of the last, so arranged that the last may be thereby engaged independently of the upper on the last, wipers adapted to be positioned at one end of the last, so arranged that the upper may be thereby wiped over the bottom of the last, upper pulling means adapted to be positioned approximately at the center of the top of the forepart of the last, back of the toe, so arranged that the upper may be thereby engaged at one side only, actuating means to actuate said upper pulling means lengthwise of the last and controlling means positioned relatively to said actuating means, so arranged that the time of the actuation of said actuating means may be thereby controlled.

79. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe and yielding heel engaging means, so arranged that the upper may be thereby held toward the last.

80. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, yielding actuating means for said upper pulling means, last holding means adapted to be positioned relatively to the last, so arranged that the last may be thereby held toward said upper pulling means, during the actuation of said upper pulling means by said actuating means and additional last holding means adapted to be positioned relatively to the last, so arranged that the last may be thereby held against said upper pulling means, after the pulling operation of said upper pulling means upon the upper.

81. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, last moving means adapted to be positioned relatively to the last, so arranged that the last may be thereby moved lengthwise of the machine to cause said upper pulling means to pull the upper lengthwise of the last, under the influence of the movement of the last by said last moving means, a lever positioned relatively to said last moving means, connections positioned relatively to said last moving means and to said lever, so arranged that the movement of said last moving means may be thereby controlled and heel engaging means adapted to be positioned relatively to the last and so arranged that the upper may be thereby held toward the last.

82. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the

upper may be thereby engaged at one side only, actuating means for said upper pulling means, a lever positioned relatively to said actuating means, connections positioned relatively to said actuating means and to said lever, so arranged that the actuation of said actuating means may be thereby retarded and heel engaging means adapted to be positioned relatively to the last and so arranged

5 that the upper may be thereby held toward the last.

83. A machine for working an upper on a last, having, in combination, last supporting means adapted to be positioned at the rear 15 part of the last, so arranged that the last may be thereby engaged independently of the upper on the last, movable upper pulling means adapted to be positioned approximately at the center of the top of the fore- 20 part of the last, back of the toe, stopping means positioned relatively to said upper pulling means to stop the movement of said upper pulling means, additional stopping means positioned relatively to said upper 25 pulling means to stop the movement of said upper pulling means and last moving means adapted to be positioned relatively to the last and so arranged that the last may be thereby moved toward said upper pulling 30 means and toward said last supporting means.

84. A machine for working an upper on a last, having, in combination, upper pulling means adapted to be positioned approximately 35 at the center of the top of the forepart of the last, back of the toe, last supporting means adapted to be positioned at the rear part of the last, so arranged that the last may be thereby engaged independently of the upper on the last, additional last supporting means adapted to be positioned relatively to the last, moving means positioned relatively to said additional last supporting means, so arranged that said additional last supporting means may be thereby moved with the last rearwardly to cause said upper pulling means to pull the upper forwardly, under the influence of the rearward movement of the last by said additional last supporting means and heel engaging means adapted to be positioned relatively to the last and so arranged that the upper may be thereby held toward the last.

85. A machine for working an upper on a last, having, in combination, last supporting means adapted to be positioned at the rear part of the last, so arranged that the last may be thereby engaged independently of the upper on the last, upper pulling means 50 adapted to be positioned approximately at the center of the top of the forepart of the last, back of the toe, last moving means adapted to be positioned relatively to the last, so arranged that movement of the last thereby may cause said upper pulling means

to pull the upper, under the influence of the movement of the last by said last moving means, actuating means for said last moving means, so arranged that the last may be thereby moved lengthwise of the machine 70 and heel engaging means adapted to be positioned relatively to the last and so arranged that the upper may be thereby held toward the last.

86. A machine for working an upper on a last, having, in combination, upper pulling means adapted to be positioned approximately at the center of the top of the forepart of the last, back of the toe, actuating means to actuate said upper pulling means lengthwise of the last, heel engaging means, so arranged that the upper may be thereby engaged and held toward the last, wipers adapted to be positioned at one end of the last, so arranged that the upper may be thereby wiped over the bottom of the last and last moving means adapted to be positioned relatively to the last and so arranged that the last may be thereby moved vertically relative to said wipers, after the engagement of said heel engaging means with the shoe.

87. A machine for working an upper on a last, having, in combination, last supporting means adapted to be positioned at the rear 95 part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, last holding means adapted to be positioned relatively to the last, so arranged that the upper may be thereby held toward the last and so arranged that the last may be thereby held toward said upper pulling means and toward said last supporting means, said first mentioned last holding means and said additional last holding means being arranged for consecutive action 110 upon the shoe.

88. A machine for working an upper on a last, having, in combination, upper pulling means adapted to be positioned approximately at the center of the top of the forepart of the last, back of the toe, actuating means to actuate said upper pulling means lengthwise of the last, yielding last holding means adapted to be positioned relatively to the last to hold the last toward said upper 120 pulling means, during the pulling operation of said upper pulling means upon the upper and non-yielding last holding means adapted to be positioned relatively to the last and so arranged that the last may be thereby 130

held toward said upper pulling means, after the pulling operation of said upper pulling means upon the upper.

89. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, yielding actuating means to actuate said upper pulling means lengthwise of the last, wipers adapted to be positioned at one end of the last, so arranged that the upper may be thereby wiped over the bottom of the last, a single actuating means for said wipers, so arranged that said wipers may be thereby actuated simultaneously at both sides of the last and heel engaging means, so arranged that the upper may be thereby held toward the last.

90. A machine for working an upper on a last, having, in combination, upper pulling means adapted to be positioned approximately at the center of the top of the forepart of the last, back of the toe, so arranged that the upper may be thereby engaged at one side only, yielding actuating means to actuate said upper pulling means lengthwise of the last, wipers adapted to be positioned at one end of the last, so arranged that the upper may be thereby wiped over the bottom of the last, simultaneously at both sides of the last and heel engaging means, so arranged that the upper may be thereby held toward the last.

91. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, heel engaging means, so arranged that the upper may be thereby held toward the last and so arranged that the last may be thereby held toward said upper pulling means, additional heel engaging means, so arranged that the upper may be thereby held toward the last, said first mentioned heel engaging means and said additional heel engaging means being arranged to engage the shoe consecutively and last holding means adapted to be positioned relatively to the last and so arranged that the last may be thereby held toward said last supporting means.

92. A machine for working an upper on a last, having, in combination, last support-

ing means adapted to be positioned at the rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last and last holding means adapted to be positioned relatively to the last, so arranged that the last may be thereby held toward said upper pulling means and toward said last supporting means and arranged to be moved to inoperative or to operative position.

93. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, adjusting means for said upper pulling means and last holding means adapted to be positioned relatively to the last and so arranged that the last may be thereby held toward said upper pulling means and toward said last supporting means.

94. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, last holding means adapted to be positioned relatively to the last, so arranged that the last may be thereby held toward said upper pulling means and toward said last supporting means and additional last holding means adapted to be positioned relatively to the last to hold the last from lengthwise movement.

95. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, last moving means adapted to be positioned relatively to the last, so arranged that the last may be thereby moved toward said upper pulling means and toward said last supporting means and

adjusting means for said last moving means, so arranged that the extent of the movement of the last by said last moving means may be thereby predetermined.

96. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, additional last supporting means adapted to be positioned at the rear part of the last and adjusting means for said additional last supporting means.

97. A machine for working an upper on a last, having, in combination, last supporting means adapted to be positioned at the rear part of the last, so arranged that the last may be thereby engaged independently of the upper on the last, movable upper pulling means adapted to be positioned approximately at the center of the top of the forepart of the last, arranged for free movement lengthwise of the last, limiting means to limit the movement of said upper pulling means toward the toe of the last and heel engaging means adapted to be positioned relatively to the last and so arranged that the upper may be thereby held toward the last.

98. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, upper working means adapted to be positioned relatively to the bottom of the last, so arranged that the upper may be thereby worked over the bottom of the last, a carriage for supporting said upper working means, said carriage being arranged to contact with and actuate said upper pulling means and heel engaging means adapted to be positioned relatively to the last and so arranged that the upper may be thereby held toward the last.

99. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, heel engaging means, a single actuating means for said upper pulling means and for said heel engaging means and last holding means adapted to be posi-

tioned relatively to the last and so arranged that the last may be thereby held toward said last supporting means.

100. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling means adapted to be positioned approximately at the center of the top of the forepart of the last, back of the toe, so arranged that the upper may be thereby pulled lengthwise of the last and so arranged that the upper may be thereby held toward the last, during the time that the upper is being wiped over the bottom of the last by said toe wipers, actuating means for said upper pulling means, so arranged that movement thereof may permit movement of said upper pulling means toward the heel, during the time of the wiping operation upon the upper by said toe wipers and heel engaging means, so arranged that the upper may be thereby held toward the last.

101. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, last holding means adapted to be positioned at the forepart of the last, so arranged that the last may be thereby held relatively to said toe wipers and toward said last supporting means, preparatory to and during the time that the upper is being wiped over the bottom of the last by said toe wipers, upper pulling means adapted to be positioned approximately at the center of the top of the forepart of the last, back of the toe, arranged for movement lengthwise of the last, toward the toe and toward the heel and stopping means positioned relatively to said upper pulling means, so arranged that said upper pulling means may be thereby stopped from movement toward the heel, after its pulling movement upon the upper toward the toe and during the application of fastenings to hold the upper in pulled condition on the last and arranged to permit said upper pulling means to be moved lengthwise of the last, toward the heel, during the time that the upper is being wiped over the bottom of the last by said toe wipers and during the time that the last is being held by said last holding means, substantially as described.

102. A machine for working an upper on a last, having, in combination, last supporting means adapted to be positioned at the rear part of the last, so arranged that the

last may be thereby engaged independently of the upper on the last, upper pulling means adapted to be positioned approximately at the center of the top of the forepart of the last, back of the toe, so arranged that the upper may be thereby engaged at one side only, yielding actuating means for said upper pulling means and heel engaging means, so arranged that the upper may be thereby held toward the last.

103. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, last holding means adapted to be positioned relatively to the last, so arranged that the last may be thereby held relatively to said toe wipers and toward said last supporting means, preparatory to and during the time that the upper is being wiped over the bottom of the last by said toe wipers, upper pulling means adapted to be positioned approximately at the center of the top of the forepart of the last, back of the toe, and actuating means to actuate said upper pulling means lengthwise of the last, toward the heel, so arranged that said upper pulling means may be thereby actuated during the time that the upper is being wiped over the bottom of the last by said toe wipers and during the time that the last is being held by said last holding means.

104. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, last holding means adapted to be positioned relatively to the last, so arranged that the last may be thereby held relatively to said toe wipers and toward said last supporting means, substantially as described, upper pulling means adapted to be positioned approximately at the center of the top of the forepart of the last, back of the toe, and yielding actuating means to actuate said upper pulling means lengthwise of the last toward the toe and actuating means to actuate said upper pulling means lengthwise of the last, toward the heel, so arranged that said upper pulling means may be thereby actuated lengthwise of the last, toward the heel, during the time that the upper is being wiped over the bottom of the last by said toe wipers.

105. A machine for working an upper on a last, having, in combination, last supporting means adapted to be positioned at the rear part of the last, so arranged that the

last may be thereby engaged independently of the upper on the last, upper pulling means adapted to be positioned approximately at the center of the top of the forepart of the last, back of the toe, so arranged that the upper may be thereby engaged at one side only, actuating means for said upper pulling means, heel engaging means, so arranged that the upper may be thereby forced toward the last, at the sides thereof, and additional heel engaging means, so arranged that the upper may be thereby forced toward the last at the heel end thereof.

106. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, actuating means for said upper pulling means, toe wipers, so arranged that the upper may be thereby wiped over the bottom of the last, during the time that the upper is under engagement of said upper pulling means and heel engaging means, so arranged that the upper may be thereby engaged and held toward the last, substantially as described.

107. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means for said upper pulling means and heel engaging means, so arranged that the upper may be thereby held toward the last, prior to the pulling operation upon the upper by said upper pulling means, substantially as described.

108. A machine for working an upper on a last, having, in combination, upper pulling means adapted to be positioned approximately at the center of the top of the forepart of the last, back of the toe, actuating means for said upper pulling means, toe wipers, so arranged that the upper may be thereby wiped over the bottom of the last, yielding heel engaging means, so arranged that the upper may be thereby held toward the last and non-yielding last holding means positioned relatively to the last and so arranged that the last may be thereby held against the strain of the wiping operation upon the upper by said toe wipers.

109. A machine for working an upper on a last, having, in combination, last supporting means adapted to be positioned at the rear part of the last, so arranged that the

last may be thereby engaged independently of the upper on the last, upper pulling means adapted to be positioned at the forepart of the last, arranged for movement lengthwise of the last, heel engaging means, so arranged that the upper may be thereby held toward the last and arranged for movement lengthwise of the last and a single stopping means positioned relatively to some 10 of said means to stop the movement of all said means toward the toe of the last.

110. A machine for working an upper on a last, having, in combination, last supporting means adapted to be positioned at the 15 rear part of the last, so arranged that the last may be thereby engaged independently of the upper on the last, toe wipers, so arranged that the upper may be thereby wiped over the bottom of the last, last holding 20 means adapted to be positioned at the forepart of the last, so arranged that the last may be thereby held relatively to said toe wipers and toward said last supporting means, during the time that the upper is 25 being wiped over the bottom of the last by said toe wipers and during the time that the toe of the upper is being worked on the last by the operator in coöperation with said toe wipers, upper pulling means adapted to 30 be positioned approximately at the center of the top of the forepart of the last, back of the toe, so arranged that the upper may be thereby engaged at one side only and so arranged that the shoe may be thereby sup- 35 ported, during the time that the upper is being wiped over the bottom of the last by said toe wipers, actuating means to actuate said upper pulling means lengthwise of the last, during the time that the upper is being 40 wiped over the bottom of the last by said toe wipers and during the time that the toe of the upper is being worked on the last by the operator in coöperation with said toe wipers and heel engaging means, so ar- 45 ranged that the upper may be thereby held toward the last.

111. A machine for working an upper on a last, having, in combination, last supporting means adapted to be positioned at the 50 rear part of the last, so arranged that the last may be thereby engaged independently of the upper on the last, upper pulling means adapted to be positioned approximately at the center of the top of the fore- 55 part of the last, back of the toe, arranged for movement lengthwise of the last and arranged to follow the lines of the last, during its movement lengthwise of the last, toe wipers, so arranged that the upper may be 60 thereby wiped over the bottom of the last, after the pulling operation of said upper pulling means upon the upper and during the continued engagement of said upper pulling means with the upper, actuating 65 means for said upper pulling means, so ar-

ranged that said upper pulling means may be thereby actuated lengthwise of the last, during the time that the upper is being wiped over the bottom of the last by said toe wipers, last holding means adapted to be 70 positioned relatively to the last and so arranged that the last may be thereby held toward said last supporting means and heel engaging means, so arranged that the upper may be thereby held toward the last. 75

112. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, last holding means adapted to be positioned at the forepart of the last, so arranged that the last may be thereby held relatively to said toe wipers and toward said last supporting means, preparatory to and during the time that the upper is being wiped over the bottom of the last by said toe wipers, upper 90 pulling means adapted to be positioned approximately at the center of the top of the forepart of the last, back of the toe, so arranged that the upper may be thereby engaged at one side only, actuating means to 95 actuate said upper pulling means lengthwise of the last, controlling means positioned relatively to said actuating means and so arranged that said actuating means may be thereby actuated, during the time 100 that the upper is being wiped over the bottom of the last by said toe wipers and during the time that the last is being held by said last holding means and heel engaging means, so arranged that the upper may be 105 thereby held toward the last.

113. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling 110 means adapted to be positioned approximately at the center of the top of the forepart of the last, back of the toe, so arranged that fastenings may be applied to hold the upper on the last as pulled by said upper pulling means, preparatory to the wiping 115 operation upon the upper by said toe wipers, yielding actuating means for said upper pulling means and last holding means adapted to be positioned at the forepart of the last and so arranged that the last may 120 be thereby held relatively to said toe wipers. 125

114. A machine for working an upper on a last, having, in combination, last supporting means adapted to be positioned at the rear part of the last, so arranged that the 130

- last may be thereby engaged independently of the upper on the last, toe wipers, so arranged that the upper may be thereby wiped over the bottom of the last, upper pulling means adapted to be positioned approximately at the center of the top of the forepart of the last, back of the toe, so arranged that fastenings may be applied to hold the upper on the last as pulled by said upper pulling means, preparatory to the wiping operation upon the upper by said toe wipers, yielding actuating means for said upper pulling means and heel engaging means, so arranged that the upper may be thereby held toward the last substantially as described.

115. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling means adapted to be positioned approximately at the center of the top of the forepart of the last, back of the toe, so arranged that fastenings may be applied to hold the upper on the last as pulled by said upper pulling means, preparatory to the wiping operation upon the upper by said toe wipers, yielding actuating means for said upper pulling means and last moving means adapted to be positioned at the forepart of the last and so arranged that the last may be thereby moved relatively to said toe wipers.

116. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling means adapted to be positioned approximately at the center of the top of the forepart of the last, back of the toe, so arranged that the upper may be thereby engaged at one side only, actuating means for said upper pulling means and heel engaging means, so arranged that the upper may be thereby held toward the last, substantially as described.

117. A machine for working an upper on a last, having, in combination, upper pulling means adapted to be positioned approximately at the center of the top of the forepart of the last, back of the toe, so arranged that the upper may be thereby engaged at one side only, yielding actuating means for said upper pulling means, heel engaging means, so arranged that the upper may be thereby held toward the last, movable last supporting means adapted to be positioned

at the rear part of the last, so arranged that the last may be thereby engaged independently of the upper on the last and stopping means, so arranged that said movable last supporting means may be thereby stopped from movement at predetermined points lengthwise of the machine for lasts of various sizes.

118. A machine for working an upper on a last, having, in combination, upper pulling means, adapted to be positioned approximately at the center of the top of the forepart of the last, back of the toe, so arranged that the upper may be thereby engaged at one side only, actuating means for said upper pulling means, a last pin to support the last, arranged for movement lengthwise of the machine on the arc of a circle, heel engaging means, so arranged that the upper may be thereby held toward the last and so arranged that the last may be thereby moved with said last pin on said arc, toward said upper pulling means and actuating means for said heel engaging means, substantially as described.

119. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling means adapted to be positioned approximately at the center of the top of the forepart of the last, back of the toe, so arranged that the upper may be thereby engaged at one side only, actuating means to actuate said upper pulling means lengthwise of the last, adjustable stopping means positioned relatively to said upper pulling means, so arranged that said upper pulling means may be thereby stopped from movement lengthwise of the last, relatively to said last supporting means, to properly support lasts of various sizes, preparatory to the pulling operation of said upper pulling means upon the upper and preparatory to the wiping operation of said toe wipers upon the upper and heel engaging means, so arranged that the last may be thereby held toward said last supporting means.

120. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling means adapted to be positioned approximately at the center of the top of the forepart of the last, back of the toe, so arranged that the upper may be thereby engaged at one side only and so arranged that the last

may be thereby supported continuously during the pulling operation of said upper pulling means upon the upper and during the time of the wiping operation upon the upper 5 by said toe wipers, yielding actuating means to actuate said upper pulling means lengthwise of the last and heel engaging means, so arranged that the upper may be thereby held toward the last.

10 121. A machine for working an upper on a last, having, in combination, last supporting means adapted to be positioned at the rear part of the last, so arranged that the last may be thereby engaged independently 15 of the upper on the last, upper pulling means adapted to be positioned approximately at the center of the top of the fore-part of the last, back of the toe, so arranged that the upper may be thereby engaged at 20 one side only, actuating means for said upper pulling means, arranged to actuate said upper pulling means lengthwise of the last, toward the toe only, and heel engaging means, so arranged that the upper may be 25 thereby held toward the last.

122. A machine for working an upper on a last, having, in combination, upper pulling means adapted to be positioned approximately at the center of the top of the fore-part of the last, back of the toe, so arranged that the upper may be thereby engaged at one side only, yielding actuating means to actuate said upper pulling means lengthwise of the last, last supporting means 30 adapted to be positioned at the rear part of the last, so arranged that the last may be thereby engaged independently of the upper on the last and arranged for movement lengthwise of the last, adjustable stopping 35 means positioned relatively to said last supporting means, so arranged that said last supporting means may be thereby stopped from movement to properly support lasts of various sizes, preparatory to the pulling operation of said upper pulling means upon 40 the upper and heel engaging means, so arranged that the last may be thereby held toward said last supporting means.

123. A machine for working an upper on a last, having, in combination, last supporting means adapted to be positioned at the rear part of the last, so arranged that the last may be thereby engaged independently 45 of the upper on the last, upper pulling means adapted to be positioned approximately at the center of the top of the fore-part of the last, back of the toe, so arranged that the upper may be thereby engaged at one side only, actuating means to actuate 50 said upper pulling means lengthwise of the last, toward the toe, adjustable means positioned relatively to said actuating means and to said upper pulling means, so arranged that the extent of the actuation of 55 said upper pulling means by said actuating

means may be thereby predetermined, for the purposes described and heel engaging means, so arranged that the upper may be thereby held toward the last.

124. A machine for working an upper on a last, having, in combination, last supporting means adapted to be positioned at the rear part of the last, so arranged that the last may be thereby engaged independently of the upper on the last, toe wipers, so arranged that the upper may be thereby wiped over the bottom of the last, upper pulling means adapted to be positioned approximately at the center of the top of the fore-part of the last, back of the tip seam of the upper on the last, so arranged that the upper may be thereby engaged at one side only and so arranged that the last may be thereby supported continuously during the pulling operation of said upper pulling means upon the upper and during the wiping operation upon the upper by said toe wipers, actuating means, to actuate said upper pulling means lengthwise of the last, arranged to permit the operator to move said upper pulling 70 means by hand, during the time that the shoe is in the machine, to predetermine the extent of the pulling movement upon the upper by said upper pulling means, in accordance with the position of the tip seam 75 of the upper relatively to said upper pulling means, prior to the actuation of said upper pulling means by said actuating means and heel engaging means, so arranged that the upper may be thereby held toward the last. 80

125. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the fore-part of the last, back of the toe, so arranged that the upper may be thereby engaged at one side only, actuating means to actuate said upper pulling means lengthwise of the last, holding means positioned relatively to said actuating means, so arranged that said actuating means may be thereby held in operative position, said actuating means being so arranged that when released by said holding means actuation may be thereby imparted to said upper pulling means and heel engaging means, so arranged that the upper may be thereby held toward the last. 100

126. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the fore- 110

- part of the last, back of the toe, so arranged that the upper may be thereby engaged at one side only, yielding actuating means to actuate said upper pulling means lengthwise 5 of the last, toward the toe, so arranged that a predetermined and approximately positive amount of movement may be imparted to said upper pulling means by said actuating means and heel engaging means, so arranged that the upper may be thereby held toward the last.

- 10 127. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means to actuate said upper pulling means lengthwise of the last, toward the toe, controlling means positioned relatively to said actuating means, so arranged that the actuation of said upper pulling means may be thereby controlled to permit said actuating means to actuate said upper pulling means a predetermined distance toward the toe and heel engaging means, so arranged that the upper may be thereby held toward the last.

- 15 128. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means to actuate said upper pulling means lengthwise of the last, co-operative means positioned relatively to said actuating means and to said upper pulling means, so arranged that said upper pulling means is dependent on said co-operative means for its actuation by said actuating means and heel engaging means, so arranged that the upper may be thereby held toward the last.

- 20 129. A machine for working an upper on a last, having, in combination, last supporting means adapted to be positioned at the rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means to actuate said upper pulling means lengthwise of the last, controlling means positioned relatively

to said actuating means, so arranged that the time of the actuation of said actuating means may be thereby predetermined, stopping means positioned relatively to said actuating means and to said controlling means to stop the actuation of said actuating means at a predetermined time and heel engaging means, so arranged that the upper may be thereby held toward the last.

130. A machine for working an upper 75 on a last, having, in combination, last supporting means adapted to be positioned at the rear part of the last, so arranged that the last may be thereby engaged independently of the upper on the last, upper pulling 80 means adapted to be positioned approximately at the center of the top of the forepart of the last, back of the toe, so arranged that the upper may be thereby engaged at one side only and arranged for movement 85 lengthwise of the last, adjustable stopping means positioned relatively to said upper pulling means, so arranged that said upper pulling means may be thereby stopped from movement lengthwise of the last, relatively 90 to said last supporting means, to properly support lasts of various sizes, preparatory to the pulling operation of said upper pulling means upon the upper and heel engaging means, so arranged that the last may 95 be thereby held toward said last supporting means.

131. A machine for working an upper on a last, having, in combination, last supporting means adapted to be positioned at the 100 rear part of the last, so arranged that the last may be thereby engaged independently of the upper on the last, upper pulling means adapted to be positioned approximately at the center of the top of the forepart of the last, back of the toe, so arranged that the upper may be thereby engaged at one side only, actuating means to actuate said upper pulling means lengthwise of the last, toward the toe, stopping means positioned relatively to said actuating means and so arranged that the actuation thereof may be thereby stopped at any desired time by the operator and heel engaging means, so arranged that the upper may 115 be thereby held toward the last.

132. A machine for working an upper on a last, having, in combination, heel engaging means, so arranged that the upper may be thereby held toward the last, last supporting means adapted to be positioned at the rear part of the last, so arranged that the last may be thereby engaged independently of the upper on the last and so arranged that it may be moved, firstly, lengthwise of the last on a plane parallel to said heel engaging means and secondly, lengthwise of the last on the arc of a circle, upper pulling means adapted to be positioned approximately at the center of the 130

top of the forepart of the last, back of the toe, so arranged that the upper may be thereby engaged at one side only and yielding actuating means to actuate said upper 5 pulling means lengthwise of the last, substantially as described.

133. A machine for working an upper on a last, having, in combination, upper pulling means adapted to be positioned at the 10 forepart of the last, heel engaging means, so arranged that the upper may be thereby held toward the last and last supporting means adapted to be positioned at the rear part of the last, so arranged that the last 15 may be thereby engaged independently of the upper on the last and so arranged that it may be moved, firstly, lengthwise of the last on a plane parallel to said heel engaging means, secondly, lengthwise of the last 20 on the arc of a circle and thirdly, perpendicularly relative to said heel engaging means.

134. A machine for working an upper on a last, having, in combination, toe wipers, 25 so arranged that the upper may be thereby wiped over the bottom of the last, upper pulling means adapted to be positioned approximately at the center of the top of the forepart of the last, back of the toe, so arranged 30 that the upper may be thereby engaged at one side only and so arranged that the last may be thereby supported during the time of the wiping operation upon the upper by said toe wipers, actuating means 35 to actuate said upper pulling means lengthwise of the last, a toe stop to hold the last from lengthwise movement, adjustable means positioned relatively to said toe stop, so arranged that said toe stop may be thereby 40 adjusted, last supporting means adapted to be positioned at the rear part of the last, so arranged that the last may be thereby engaged independently of the upper on the last and arranged for movement lengthwise 45 of the last and heel engaging means, so arranged that the upper may be thereby held toward the last.

135. A machine for working an upper on a last, having, in combination, toe wipers, so 50 arranged that the upper may be thereby wiped over the bottom of the last, upper pulling means adapted to be positioned approximately at the center of the top of the forepart of the last, back of the toe, so 55 arranged that the upper may be thereby engaged at one side only and so arranged that the last may be thereby supported during the time of its pulling operation upon the upper and during the time of the wiping 60 operation upon the upper by said toe wipers, actuating means to actuate said upper pulling means lengthwise of the last, a toe stop to hold the last from lengthwise movement, last supporting means adapted to be 65 positioned at the rear part of the last, so

arranged that the last may be thereby engaged independently of the upper on the last and arranged for movement lengthwise of the last and heel engaging means, so arranged that the upper may be thereby held 70 toward the last.

136. A machine for working an upper on a last, having, in combination, last supporting means adapted to be positioned at the rear part of the last, so arranged that the last 75 may be thereby engaged independently of the upper on the last, upper pulling means adapted to be positioned approximately at the center of the top of the forepart of the last, back of the toe, limiting 80 means positioned relatively to said upper pulling means to limit the movement of said upper pulling means toward the toe, and heel engaging means, so arranged that the upper may be thereby held toward the last. 85

137. A machine for working an upper on a last, having, in combination, last supporting means adapted to be positioned at the rear part of the last, so arranged that the last 90 may be thereby engaged independently of the upper on the last, upper pulling means adapted to be positioned approximately at the center of the top of the forepart of the last, back of the toe, actuating means to 95 actuate said upper pulling means lengthwise of the last, toward the toe, limiting means positioned relatively to said upper pulling means, so arranged that the movement of said upper pulling means toward the toe may be thereby limited and heel engaging 100 means, so arranged that the upper may be thereby held toward the last.

138. A machine for working an upper on a last, having, in combination, last supporting means adapted to be positioned at the 105 rear part of the last, so arranged that the last may be thereby engaged independently of the upper on the last, upper pulling means adapted to be positioned approximately at the center of the top of the forepart of the last, back of the toe, actuating means to actuate said upper pulling means lengthwise of the last, toward the toe, limiting means positioned relatively to said upper pulling means, so arranged that the movement of said upper pulling means toward the toe may be thereby limited, adjusting means positioned relatively to said 110 limiting means, so arranged that said limiting means may be thereby adjusted at predetermined points and heel engaging means, so arranged that the upper may be thereby held toward the last. 115

139. A machine for working an upper on a last, having, in combination, toe wipers, 120 so arranged that the upper may be thereby wiped over the bottom of the last, upper pulling means adapted to be positioned relatively to the upper, so arranged that the upper may be thereby pulled on the last pre- 125

130

paratory to the wiping operation upon the upper by said toe wipers, yielding actuating means for said upper pulling means, last supporting means adapted to be positioned at the rear part of the last, so arranged that the last may be thereby engaged independently of the upper on the last and arranged for movement lengthwise of the machine for properly supporting lasts of various sizes and heel engaging means, so arranged that the upper may be thereby held toward the last.

140. A machine for working an upper on a last, having, in combination, toe wipers, so arranged that the upper may be thereby wiped over the bottom of the last, upper pulling means adapted to be positioned relatively to the upper, so arranged that the shoe may be thereby supported and so arranged

that the upper may be thereby pulled on the last, preparatory to the wiping operation upon the upper by said toe wipers, and arranged for movement lengthwise of the last for properly supporting shoes of various sizes, yielding actuating means for said upper pulling means, last supporting means adapted to be positioned at the rear part of the last, so arranged that the last may be thereby engaged independently of the upper on the last and heel engaging means, so arranged that the upper may be thereby held toward the last.

In testimony whereof, I have affixed my signature, in the presence of two witnesses.

EUCLID I. LA CHAPELLE.
